DESIGN FOR A JAR OR SIMILAR CONTAINER

Turney H. Stough, Jeannette, Pa.

Application August 30, 1938, Serial No. 79,641

Term of patent 14 years

To all whom it may concern:

Be it known that I, Turney H. Stough, a citizen of the United States of America, residing at Jeannette, in the county of Westmoreland and State of Pennsylvania, have invented a new, original, and ornamental Design for Jar or Similar Container, of which the following is a specification, reference being had to the accompanying drawing, forming part thereof.

In the drawing:—

Figure 1 is a perspective view of a jar or similar container, showing my new design;

Figure 4 is an elevational view of the rear end portion of my jar or similar container; and

I claim:—

The ornamental design for a jar or similar container, as shown.

TURNEY H. STOUGH.
